J. H. Sandburg, ATTORNEY

UNITED STATES PATENT OFFICE.

OLGA BERGHORN, OF JERSEY CITY, NEW JERSEY.

KEY-DRESS.

1,220,171.

Specification of Letters Patent. Patented Mar. 27, 1917.

Application filed December 26, 1916. Serial No. 139,063.

To all whom it may concern:

Be it known that I, OLGA BERGHORN, a citizen of the United States, and a resident of Jersey City Heights, Jersey City, in the 5 county of Hudson and State of New Jersey, have invented a certain new and useful Improvement in Key-Dresses, of which the following is a specification.

The object of the invention is to provide 10 a means for enabling women to carry keys in a safe and sightly manner. The device, which I call a key dress, comprises a small curtain-like inclosure of ornamental flexible material of a size to accommodate a 15 key, the inclosure being open at the bottom and provided at the top with apertured plates or frame members, whereby the device may be worn or carried upon a chain, ribbon or ring, with the key suspended and 20 concealed in condition for instant use.

In the accompanying drawing:

Figure 1 is a perspective view of one form 25 of the device;

Fig. 2 is a side elevation of the same, with the key therein sustained by a chain or suspension element;

Fig. 3 is a vertical section taken at right angles to Fig. 2;

Fig. 4 is a plan view of another form, 30 spread out flat and with the top plates tilted away from each other for clearness of illustration; and

Fig. 5 is a side elevation of this form as it hangs when in use.

The drawing, Figs. 1 to 3, shows a tubular pocket or curtain 1 made of metal mesh fabric and of approximately a size to accommodate a key. The top links at two opposite sides of this curtain are engaged 40 with small openings in two flat plates 2 of suitable form and appearance, having apertures 3 for the passage of a chain 4, by which the device is suspended. In practice the key is placed within the device through 45 the mouth 5 between the plates, and the chain or other suspension element is passed through the opening in its head. Sustained in this manner the key is ready for use at any time by merely grasping the plates 2

and pushing back the flexible curtain to 50 clear the shank, or, if desired, the key can be lowered out of the inclosure.

The curtain may be constructed of other kinds of flexible and ornamental material, though mesh fabric is desirable because of 55 its appearance, making it suitable, for example, for a chatelaine, and also because its weight enables it to be shaken back by a quick movement of the hand to expose the part of the key which is inserted in the 60 lock. The lower part of the key dress may be slit or indented from the bottom, as indicated by the fringe 6, to facilitate the collapsing of the wall when the key is used.

Figs. 4 and 5 illustrate another form, 65 wherein the curtain 1^a is made of a flat piece of fabric, having a central mouth opening 5^a to the sides of which the plates 2 are secured. When the curtain is suspended from these plates it hangs in the 70 manner shown in Fig. 5. This form of curtain is readily reversed by merely inverting the plates, when the curtain falls outward and backward by its own weight exposing all of the key but the portion of 75 the head between the plates.

It will be understood that the invention may take other forms and that the sizes may be appropriately varied for keys of different kinds. If desired the device may 80 be constructed to accommodate more than one key.

What I claim as new is:

1. A key dress comprising a small inclosing curtain of ornamental flexible material 85 adapted to accommodate a key, the inclosure being open at the top and bottom, and suspension members secured to its top whereby the dress and key may be suspended by a chain or the like passed therethrough.

2. A key dress comprising an inclosing curtain of metal mesh fabric adapted to accommodate a key, in combination with apertured plates secured to opposite sides 95 of the top of said curtain to receive a suspension element passed therethrough and through the opening in the head of the key.

3. A key dress comprising a curtain adapted to accommodate a key, open at the bottom, and having suspension frame members secured to its top, whereby the dress and the key may be suspended by a chain or the like passed therethrough.

4. The combination of a flexible inclosing

curtain adapted to conceal a key and being open at the bottom, frame members secured to the top of the curtain, and suspension means adapted to pass through said members and the key within.

OLGA BERGHORN.
